UNITED STATES PATENT OFFICE.

JESSE J. MITCHELL, OF PARKERSBURG, WEST VIRGINIA.

AUTOMATIC TRAIN-PIPE COUPLING.

1,181,915.

Specification of Letters Patent.

Patented May 2, 1916.

Application filed November 6, 1915. Serial No. 60,068.

To all whom it may concern:

Be it known that I, JESSE J. MITCHELL, a citizen of the United States, residing at Parkersburg, in the county of Wood and 5 State of West Virginia, have invented new and useful Improvements in Automatic Train-Pipe Couplings, of which the following is a specification.

This invention relates to certain novel and 10 useful improvements in automatic coupling device for train line air pipes and signal and steam pipes.

In carrying out the present invention it is 15 my purpose to provide a coupling device of the class described which will embrace the desired features of simplicity, efficiency and durability, wherein the component parts will be so arranged and correlated that the same may have relative movement when 20 rounding curves and traveling over uneven road beds, and which will operate effectively for its intended purpose under all conditions.

With the above recited objects in view and 25 others of a similar nature the invention consists in the construction, combination and arrangement of parts hereinafter set forth in and falling within the scope of the claims.

In the accompanying drawings, Figure 1 30 is a view in side elevation of an automatic coupler constructed in accordance with my present invention. Fig. 2 is a top plan view of the same. Fig. 3 is a longitudinal sectional view on the line 3—3 of Fig. 2. Fig. 35 4 is a cross sectional view on the line 4—4 of Fig. 2. Fig. 5 is a cross sectional view on the line 5—5 of Fig. 2. Fig. 6 is a rear end elevation of the coupler.

Referring now to the drawings in detail 1 40 designates a plate adapted to be fastened to the car body at one end thereof and to depend from such body and formed in the plate 1 approximately centrally thereof is an opening 2. Fastened to the back of the 45 plate 1 and projecting rearwardly therefrom beneath the car body are frames 3 spaced apart transversely of the car and arranged parallel with each other. In the present instance each frame 3 embodies a bottom bar 5, a top bar 5 and a rear end bar 6 interconnecting the top and bottom bars at the rear ends thereof, the forward ends of the top and bottom bars being flanged outwardly as at 7 and fastened to the plate 1. Mounted 50 within the alining openings in the top and bottom bars of the respective frames 3 are

vertical rods 8 disposed adjacent to the rear end bars 6 of the frames and surrounding each rod 8 are counter-acting coiled expansion springs 9 arranged one above the other. 60

10 designates a substantially rectangular, or other shaped frame, arranged across the space between the frames 3—3 at the rear ends thereof and having the opposite ends formed with outwardly projecting lugs 65 11—11 respectively formed with openings that receive the rods 8. These lugs 11 are disposed between the springs 9 on the respective rods 8 and the springs, counteracting each other, acting to hold the frame 10 70 in normal position, and, at the same time, permit the frame to move vertically whenever necessary.

The frame 10 is disposed in alinement with the opening 2 in the plate 1 and mounted between the top and bottom bars of the frame 10 is the yoke 12 formed on one end of a sleeve 13 and slidably mounted within the remaining end of the sleeve 13 is one end portion of a stem 14 projecting through the 80 opening 2 and having the outer end thereof equipped with a coupler head 15 formed with a series of passages 16, opening on to the outer end of the head and designed for connection with the signal hose, air hose and 85 the steam hose respectively. The end portion of the stem 14 within the sleeve 13 is preferably round in cross section while the end portion of the stem within the opening 2 is preferably angular in cross section and 90 conforms to the shape of the opening so as to hold the stem and the head against turning movement. At the juncture of the round portion with the square portion the stem is formed with a groove 17 and surrounding the grooved portion of the stem and secured thereto is a collar 18 while surrounding the stem and the sleeve 13 between the collar 18 and the shoulder formed by the yoke 12 is a coiled expansion spring 19 having one extremity bearing against the collar and the other end engaging the yoke. This spring 19 acts to cushion the shock when two 100 couplers are brought together so as to reduce the vibration of the parts. Mounted with 105 in the sleeve 13 is a hollow piston 20 having the inner end thereof opening into the sleeve and communicating with a bore 21 formed in the rounded end portion of the stem 14 and the outer end projecting from the sleeve into 110 the yoke 12 and formed with a port 22 connected through the medium of a flexible hose

23 with a branch pipe 24 tapped on to the train line air pipe 25. Connected in the branch pipe 24 is a cut off cock 26 and an automatic pressure operated relief valve 27.

5 28-28 designate substantially V-shaped links having the apices thereof disposed in engagement with the respective limbs of the yoke 12 above and below the outer end of the piston 20, and formed in the outer end 10 of the piston 20, the apices of the links 28 and the limbs of the yoke 12 are alining openings through which is passed a pin 29 whereby a pivot connection is formed between the yoke and the piston and a pivot formed 15 for the links 28. The ends of the V-shaped links project toward the plate 1 and the corresponding ends of the links are connected with one end of a pivot rod 30. These rods 30 are disposed at opposite sides of the 20 sleeve 12 and stem 14 and the forward extremities thereof are pivotally secured to brackets 31 carried by the rear side of the plate or adjacent to the respective ends of such plate.

25 In practice the air from the train line air pipe is led into the hollow piston 20 by means of the cock 26 and as the air enters the piston such air acts upon the inner end of the piston and the outer end of the bore 30 21 in the stem 14 thereby separating the piston and the stem and acting to hold the stem and coupling head normally at the longitudinal medial line of the coupler. When two couplers are joined together the air in 35 the hollow piston holds the couplers normally in alinement and maintains the parts of the respective couplers in normal position. When, however, the coupled cars round a curve, the action of the air is overcome and the sleeves 13 and stems 14 carrying the coupler head adjust themselves to the curve and swing about the pins 29, the yokes 12 and links 28 moving horizontally in the rounding of the curve. After the curve 40 45 has been passed the air reacts to restore the sleeve and stem to normal position. The opening 2 in the plate 1 is preferably in the form of a horizontal slot to permit the stems to swing as just described, and secured to the outer face of the plate 1 at opposite ends of the slot 2 are vertical guides 32 within which are slidably mounted the ends of a horizontal rod 33 arranged across slot 2 and forming a support for the outer end of the 50 55 stem 14. Arranged below the rod 33 adjacent to the respective guides 32 are brackets 34 and projecting upwardly from the brackets 34 are stems 35 extending through the openings in the rod 33. Surrounding 60 65 the respective stems 35 are coiled expansion springs 36 while threaded on to the upper ends of the stem 35 are nuts 37 that act to limit the upward movement of the rod 33 under the action of the springs 36. The 65 70 75 80 85 90 95 100 105 110 115 120 125 130 springs 36 check the weight of the stem 14 and coupler head thereon and coact with the springs 9 to permit the coupler head, stem and sleeve to move vertically when the car is passing over any uneven road bed.

In the present instance the outer end of 70 the head 15 is equipped with contacts 16' connected with the telephone wires on the car and designed to connect the telephone wires on the respective cars of the train in circuit formation.

75 From the foregoing description taken in connection with the accompanying drawings the construction, mode of operation and manner of employing my improved coupler will be readily understood. The coupler is 80 preferably disposed below the car coupler and will effect the connection between the brake pipes, signal pipes, steam pipes and telephone wires as soon as the cars are coupled together.

85 It will, of course, be understood that each of the cars is equipped with a coupling device constructed in accordance with my present invention and, in practice, a pressure retaining valve is preferably located in the 90 branch pipe leading from the air brake pipe to the hollow piston so as to prevent the air from returning to the air brake pipe in the event of a reduction of the pressure in such pipe.

95 I claim:—

1. An automatic coupler of the class described comprising a supporting plate formed with a horizontal slot, frames secured to one side of said supporting plate 100 and projecting outwardly therefrom and spaced apart in parallelism, a stem having one end projecting through said slot and the other end disposed between said frames, a coupler head on the outer end of said 105 stem, a sleeve surrounding the inner end of the stem, a shock absorbing spring surrounding said sleeve and the inner portion of said stem having one end bearing against the stem and the remaining end engaging 110 the sleeve and a pivotal connection between the end of the sleeve remote from the stem and said frames whereby the stem and coupler head may swing horizontally.

115 2. An automatic coupler of the class described comprising a supporting plate formed with a horizontal slot, frames secured to one side of said supporting plate and projecting outwardly therefrom and spaced apart in parallelism, a stem having one end projecting through said slot and the other end disposed between said frame, a coupler head on the outer end of said stem, a sleeve surrounding the inner end of said stem, a shock absorbing spring surrounding 120 125 said sleeve and the inner portion of said stem having one end bearing against the stem and the remaining end engaging the sleeve and a pivotal connection between the end of the sleeve remote from the stem and 130

said frames whereby the stem and coupler head may swing horizontally and means holding said sleeve and stem in normal position and adapted to restore the same to such position succeeding the swinging thereof.

3. An automatic coupler of the class described comprising a supporting plate formed with a horizontal slot, frames secured to one side of said supporting plate and projecting outwardly therefrom and spaced apart in parallelism, a stem having one end projecting through said slot and the other end disposed between said frames, a coupler head on the outer end of said stem, a sleeve surrounding the inner end of the stem, a shock absorbing spring surrounding said sleeve and the inner portion of said stem having one end bearing against the stem and the remaining end engaging the sleeve and a pivotal connection between the end of the sleeve remote from the stem and said frames whereby the stem and coupler head may swing horizontally and pneumatic means holding said sleeve and stem in normal position and adapted to restore the same to such position succeeding the swinging thereof.

4. An automatic coupler of the class described comprising a supporting plate formed with a horizontal slot, frames secured to one side of said supporting plate and projecting outwardly therefrom and spaced apart in parallelism, a stem having one end projecting through said slot and the other end disposed between said frames, a coupler head on the outer end of said stem, a sleeve surrounding the inner end of the stem, a shock absorbing spring surrounding said sleeve and the inner portion of said stem having one end bearing against the stem and the remaining end engaging the sleeve and a pivotal connection between the end of the sleeve remote from the stem and said frames whereby the stem and coupler head may swing horizontally and means supporting said sleeve and stem for vertical movement.

In testimony whereof I affix my signature in presence of two witnesses.
